F. C. KELLEY

PUMP

Filed July 8, 1924

UNITED STATES PATENT OFFICE.

FRANK C. KELLEY, OF LONG BEACH, CALIFORNIA, ASSIGNOR OF ONE-HALF TO ELMER W. RIGGLE, OF LOS ANGELES, CALIFORNIA.

PUMP.

Application filed July 8, 1924. Serial No. 724,775.

To all whom it may concern:

Be it known that I, FRANK C. KELLEY, a citizen of the United States, residing at Long Beach, in the county of Los Angeles and State of California, have invented new and useful Improvements in Pumps, of which the following is a specification.

This invention relates to pumps, and has for an object to provide a novel form of pump wherein and whereby a close fitting plunger may be utilized, and which plunger is lubricated by novel means and in such a manner that fine sand is prevented from collecting between the plunger and cylinder which would abrade and wear down the plunger.

The inventor is aware of the fact that there are on the market at the present time certain pumping devices which are adapted to prevent sand from rapidly abrading or ruining a plunger, but such devices employ a plunger which has a loose working fit within the plunger barrel, and as a consequence the pumping operation is not as efficient as it would be if a tight fitting plunger were employed. However, to apply a tight fitting plunger would render the system and method used where a loose fitting plunger is utilized, inoperative.

A further object of the present invention is to provide means and a system therefor whereby sand is prevented from blocking the pump rod. A further object is to provide in a pumping device a suitable lubricating system which will prevent any rolling of metal between a tight fitting plunger and its working barrel.

With the above and other objects in view, including superiority in respect of inexpensiveness, simplicity, and general serviceability, the invention contemplates an improved pumping device which is extremely efficient, which will increase the normal outflow of oil during a pumping operation over any known system which employs a loose fitting plunger, and which consists in the novel and useful provision, formation, construction, association and relative arrangement of parts, members and features, all as shown in certain embodiments in the foregoing drawing, described generally, and finally pointed out in claims.

In the drawing:

Figure 1 is a fragmentary side elevation showing a well rig and means for pumping

oil or other fluid through casing from oil bearing strata;

Figures 2 and 3 are fragmentary cross sectional views upon an enlarged scale showing a working barrel having a liner therein with a plunger member within the liner, said showing incorporating the invention;

Figure 4 is a fragmentary cross sectional longitudinal view on an enlarged scale of the showing of Figures 2 and 3, and taken on the lines 4—4 of such figures; and,

Figure 5 is a fragmentary cross sectional view of a modified form of the invention.

Referring with particularity to the drawing, the improved pump is designated as an entirely in one embodiment by A, and it is to be noted that the particular form of pump in such figures is of the type known as a "displacement pump." In Figure 1, I have shown one method employing the pump utilizing what is known as the walking-beam system, there being a walking beam as shown at 1 operated by suitable means shown at 2 with a polish rod 3 between the walking-beam and a hollow sucker rod *a*. A suitable conduit or line 4 connects with the top of such sucker rod through a flexible coupling 5 so that oil may be pumped from the oil bearing strata up through such sucker rod to a suitable reservoir. At 6 I have shown a tank within which is oil under pressure, the oil being clean of any sand or deleterious substances. An oil well derrick is shown at *b*, and as is usual various lengths of casing as shown at 7, 8 and 9 are employed which casing extends within a well hole. The perforated casing within the well hole is shown at 10 and a surrounding screen at 11. This perforated casing 10 is connected to the working barrel *c* by means of a suitable coupling 12, and the working barrel is likewise associated with one of the lengths of casing through the medium of a suitable connector 13.

Referring to Figure 2 it will be seen that the working barrel *c* is interposed between the two unions or connectors 12 and 13, and the union 13 is internally screw-threaded as shown at 20 for reception therein of a screw-threaded end 21 of the working barrel *c*. Likewise the said connector or union is flanged internally as shown at 22. The connector or union 12 is similarly formed and reference characters just applied for the 110

connector 13 are applied to this last named connector. Adapted to be placed within the working barrel and spaced from the inner surface thereof is a liner *d*, which liner is 5 provided at its ends with screw threads 23 and 24 respectively, and collar members 25 and 26 are screw-threaded upon such respective ends, with the said collar members plus the end portions of the liner received 10 within the unions or connectors, and bearing against the inwardly directed flange 22 of the connector 13 and the flange 27 of the connector 12. It will thus be seen that this method will ensure a proper holding of the 15 liner within the working barrel and between the said connectors or unions 12 and 13. The hollow sucker rod *a* is screw-threaded to a working valve *e* and said working valve *e* is in turn associated with a hollow plunger 20 *f* through the medium of a union or coupling *g*. The lowermost portion of such hollow plunger carries an internal ring member 30, and a standing valve *h* is seated within the union or connector 12, as shown 25 at 31, with a Garbutt rod 32 connected to the cage of such standing valve and passed inwardly of the hollow plunger *f*, such rod carrying a cross head or *T* 33, which, when it is desired to "pull" the tubing would 30 contact with the collar 30 so as to lift the standing valve from its seat 31. The standing valve *h* is conventional in form, including the usual cage member 34 within which is a ball 35 adapted to seat and close an opening 35 communicating with the cage and the perforated tubing 10, in a well understood manner. The working valve *e* is of slightly different form and includes an annulus 36 having an internal flange 37 within which 40 is received a member 38 forming a valve seat for a ball member 39. Spaced above the ball member 39 and connected with the annulus 36 is a diametrically disposed stop pin 40 which acts to limit upward movement of the ball 39 within the annulus. The 45 sucker rod *a* is directly connected to the annulus 36 by screw-threading or otherwise, as shown at 41. A back pressure valve *j* is disposed between the pin 40 and the lower 50 end of the sucker rod *a*, and the said back pressure valve includes a casing 42 transversely disposed within the annulus 36, such casing being formed with two axial bores 43 and 44, and with a transverse bore 45 communicating with the bore 44. The bore 43 55 communicates exteriorly of the annulus 36, and the bore 45 permits communication with the space within the annulus 36 and the bore 44. Within the bore 44 is a ball 46 normally urged through the medium of a spring or 60 the like 47 to close communication between the bores 43 and 44.

The operation of the form of device just described, is as follows:

65 The plunger member *f* has a close working

fit with the inner surface of the liner *d* and as is usual the liner has a highly polished inner surface to aid in reduction of friction. In ordinary pumping the oil is usually heavily laden with sand and other substances 70 which tend to get between the plunger and the liner and to rapidly cut and abrade the surface of such liner and plunger, often so badly sanding up the well as to necessitate a pulling of the plunger from the well. In 75 fact, in some wells located in California the plungers are pulled as often as five time a month and new pumps placed in the well. The present device, as will more clearly follow, effectively prevents the necessity of 80 replacing a pump, and at the same time prevents a sanding up of the pump and at all times keeps the plunger and liner free from sand. The present form of pump is of 85 the displacement type, as has been stated, and the oil to be lifted is pumped through the hollow sucker rod *a*. A regulated amount of clean fresh oil is passed from the tank 6 where it is confined under pressure 90 or fed from said tank under pressure 95 through a pipe 50 through the casing. Such oil would enter, as Figure 2 shows, between the casing 9 and sucker rod *a* within the liner *d*, and near the coupling or union 12 are transverse openings or ports 51 in the liner *d*. These ports permit communication 100 within the liner and to the space included between the liner and the inner surface of the working barrel *c*. Oil passed downwardly through the various lengths of casing will naturally fill the space included between the sucker rod *a* and the inner surface of the liner *d*, as well as the space included 105 between the outer surface of the working valve and the inner surface of the liner to the top of the hollow plunger *f*. This is also shown in enlargement in Figure 4.

The plunger *f* has a certain length of working stroke, and Figure 2 illustrates the lowermost stroke of such plunger. Ports 60 are likewise transversely disposed within the liner *d* and the ports 51 and 60 are so disposed that the ports 51 are never closed when the plunger reaches its uppermost excursion, 110 and the ports 60 never open; that is to say, the ports 60 would never allow communication with the interior of the liner and the space included between the liner and working barrel, but would at all times only permit communication from the space included 115 between the liner and working barrel and a portion of the surface of the plunger. An annular groove 62 is in direct communication with such ports 60 so that any oil passed through such ports will naturally fill such 120 annular groove and this will keep the surface of the plunger lubricated during its working strokes.

As the plunger is lowered the fresh oil 130 will pass from the space included between

the sucker rod, working valve and the inner surface of the liner, in part through the ports 51, down within the space included between the liner and the working barrel and into the ports 60. During an up-stroke of the plunger the oil immediately above such plunger and within the liner might cause a back pressure and the back pressure valve *j* will open to allow a certain amount 10 of the oil to pass inwardly of such valve and outwardly through the port 45 and be lifted with the oil being pumped. Thus it will be seen that a film of fresh, clean oil is at all times maintained between the liner and the 15 outer surface of the plunger and that the pressure of such oil will effectively prevent sand from getting between the liner and the plunger. The pressure of the fresh oil is sufficient to prevent any oil being pumped 20 through the sucker rod from entering between the plunger and the liner. Furthermore, the back pressure valve by allowing a certain amount of the fresh oil under pressure to enter into the column of oil being 25 pumped aids in keeping the oil being pumped agitated so as to prevent a settling of any sand within the working valve.

Figure 5 does not differ essentially from the showing of the apparatus just described, 30 and shown in Figures 1 to 4 inclusive, with the possible exception that no liner is used. The working barrel is adapted to confine the plunger *f* and a by-pass pipe 70 communicates through the medium of couplings 35 71 and 72, with ports 73 and 74 passed through such working barrel. The port 74 communicates directly with an internal annular groove 75, and the location of such ports would be the same as the location of 40 the ports 51 and 60 for the device shown in Figures 1 to 4 inclusive. A standing valve and working valve similar to the ones previously described would be utilized and the 45 operation in all particulars would be the same in that oil would be pumped under pressure within the working barrel which in part would be by-passed through the pipe 70, and the oil being pumped from the oil-bearing strata would be passed through the 50 hollow plunger and through the hollow sucker rod. This by-passing of oil, in either form of the device shown, to the lowermost portion of the plunger effectively prevents the plunger from freezing, whether within 55 the liner or the working barrel.

Furthermore, a circulation of the fresh oil either under pressure or by gravity through the back pressure valve above the plunger, aids in filtering the sand as it is 60 passed through the working valve and effectively prevents the sand from sanding up the hollow pump rod or sucker rod, while being delivered to the surface of the well. 65 With a tight fitting plunger it is of course possible to pump more oil or water within

a given period of time than could be possible by pumping with a loose fitting pump. The temperature within a well hole is a factor to be considered, as it often happens that hot oil is encountered which tends to 70 expand the plunger within the working barrel. However, with my system the plunger is at all times properly lubricated so that regardless of this expansion a fairly free working action is at all times maintained, 75 whereas, with the old method of pumping where a tight-working plunger is employed the plunger would often freeze under the same conditions.

It is obvious that various changes and 80 modifications and variations may be made in practicing the invention, in departure from the particular showing of the drawing, without departing from the true spirit 85 of the invention.

Having thus disclosed my invention, I claim and desire to secure by Letters Patent:

1. A pump of the character disclosed, including a liner, a working barrel surrounding said liner and spaced therefrom, ports 90 disposed in said liner and permitting communication between the liner and the interior of the working barrel, a plunger within such liner, certain of the ports being so disposed within the liner that they are at 95 all times covered by the plunger during its working strokes.

2. A pump of the character disclosed, including a liner, a working barrel surrounding said liner and spaced therefrom, ports 100 disposed in said liner and permitting communication between the liner and the interior of the working barrel, a plunger within such liner, certain of the ports being so disposed within the liner that they are at 105 all times covered by the plunger during its working strokes while other of such ports are at all times open.

3. A pump of the character disclosed, including a hollow plunger, a liner within 110 which said plunger is disposed for reciprocation, said liner and plunger being in close working engagement; a standing valve and a working valve, a tubing surrounding said liner and spaced therefrom, a hollow sucker 115 rod associated with the working valve, said standing valve and said working valve opening and closing during a pumping operation to force fluid through the hollow sucker rod, and means for forcing lubricating fluid between the liner and tubing surrounding the liner and against the plunger and between the working surfaces of the liner and plunger; further means being provided for in part passing lubricating fluid within the 120 hollow sucker rod.

In testimony whereof, I have signed my name to this specification.

FRANK C. KELLEY.
